FOLDING CHAIR

Filed June 10, 1924

UNITED STATES PATENT OFFICE

CLIFFORD J. MARSON, OF CAMBRIDGE CITY, INDIANA, ASSIGNOR TO THE STANDARD MANUFACTURING COMPANY, OF CAMBRIDGE CITY, INDIANA, A CORPORATION OF INDIANA

FOLDING CHAIR

Application filed June 10, 1924. Serial No. 719,078.

Broadly stated my object is to provide a folding chair of simple and inexpensive construction, easily operated and handled, so constructed that it will fold into a minimum of space in such manner that there will be no projecting parts, and by which they may be stacked compact, will not inadvertently tip or collapse when in operative position, and which can be manufactured and sold at a comparatively low price.

Other specific objects and particular advantages of the invention will suggest themselves in the course of the following description, and that which is new will be correlated in the appended claims terminating this specification.

The specific means for carrying out the principles of this invention in a practical and efficient manner is shown in the accompanying drawings, in which—

Figure 1 is a perspective front view of a chair constructed in accordance with my invention. Figure 2 is an edge view or side elevation of the same.

Figure 3 is a perspective view of one of the two pivotal sleeves.

Figure 4 is a detail side elevation of a portion of one side of the chair showing the position of the back when the chair is open.

Figure 5 is a detail section showing the manner of hanging the back. Figure 6 is a central longitudinal section of a portion of one of the legs showing the rear edge of the seat and the manner of mounting the same.

And Figure 7 is an inside-face view of a portion of one of the legs.

Similar indices denote like parts throughout the several views.

In order that the construction, the operation, and the advantages of the invention may be more fully understood and appreciated, I will now take up a detailed description thereof in which I will set forth the same as comprehensively as I may.

The body of my chair comprises the stand,

ards 1 and 2, which are spaced apart parallel with each other and are rigidly connected by the top bar 3 and the rung 4, thereby forming a frame.

The legs 5 and 6 contact, at their upper ends, with the inner faces of the respective members 1 and 2. The upper ends of said legs are pivoted at their upper ends at points slightly above the centers of the members 1 and 2, by means of the rivets 7 and 8, respectively. And said legs are rigidly connected together, near their lower end by the rung 9.

The back comprises the side members 10 and 11, connected at their upper and lower ends by the respective top member 12 and bottom member 13, thereby forming a rigid frame, enclosing the slats or other fillers 14.

The top member 12 is located slightly below the upper ends of the members 10 and 11, forming projections through which aligned apertures are formed horizontally to receive the rod 15, which rod extends through the members 1 and 2 in such position that the back may swing, with the upper ends of the members 10 and 11 only slightly below the bar 3, as shown in Fig. 1.

The seat is similar in construction to the back, it having side members 16 and 17 and the end members 18 and 19 all rigidly secured together forming a rigid frame enclosing the slats or other filler 20.

The seat is of such width as to fit between the members 1 and 2 to which it is hinged by means of the rod 21 which extends through aligned apertures formed horizontally through the members 16 and 17 at a position rearward of the central portions of said members. The ends of said rod 21 extend through the members 1 and 2 and are riveted in the outer faces thereof as indicated.

Rearward of the rod 21 the rear corners of the seat are cut away, as shown at X in Fig. 1, whereby the width of the rear portion of the seat is reduced to such extent that it will fit between the legs 5 and 6, as shown in Fig. 1.

Likewise the lower corner portions of the back are cut away, as shown at Y in Fig. 1, whereby the width of the lower portion of the back is reduced to such extent that it will swing between the legs 5 and 6, as indicated in Fig. 1.

Each of the pivotal sleeves comprises a plate 22 and two flanges 23 and 24, which flanges are turned at right angles to said plate 10 and parallel with each other, all being formed of a single portion of sheet metal. Extending out, opposite to the flanges, and central of one end of the plate, is a screw or pivot 25. Said sleeves are located in slidable contact 15 with the lower edge portions of the back, that is with the members 10 and 11, which members are slidable between the flanges 23 and 24 and the plate 22. The pivots 25 are rotatably mounted each in its respective socket 26 and 27, as shown in Figs. 6 and 7, respectively.

Formed in the inner faces of the legs 5 and 6, extending longitudinally thereof, are the channels 28 and 29, respectively.

A pair of metal hangers 30 and 31 are provided, they being secured to the rear corners of the seat, each having an outwardly extending pivot 32, integral therewith. Said pivots are located in the respective channels 28 and 30 29, and they are adapted to slide from end to end thereof, as hereinafter described.

The operation of the chair is very simple: Being constructed as above set forth, the chair is rendered capable of being folded to the 35 position shown in Fig. 2, whereby there will be no parts projecting beyond the edges of the standards 1 and 2.

To open the chair one has only to turn the seat from vertical to substantially horizontal 40 position, with the standards extending up and down, or nearly so. In this movement it will be seen that the pivots 32 will slide in their channels 28 and 29, thereby projecting the legs back and at an angle to the positions 45 in which they are shown in Figs. 1 and 4. Said pivots engaging the upper ends of said channels will prevent the seat from moving down beyond horizontal position, and when the chair is closed the said parts will engage with the lower ends of said channels.

It will be apparent that the pivots 25, being located in their respective sockets 26 and 27, that as the legs 5 and 6 move outward to 55 open position the sleeves will be carried rearward, thereby moving the lower end of the back rearward, turning it on the rod 15 at its upper end, thereby bringing the back to operative position at an angle different from that of the standards or the legs. This last 60 mentioned operation being made possible by reason of the lower end of the back sliding in said sleeves, but at all times limited in its swinging operation by the flanges of the sleeves.

From the above it will be observed that

the distinctive feature is that my chair has a swinging back, as well as a swinging or foldable seat, and that the back is adapted to move automatically.

It is to be understood that the pivots 25 70 may not be integral with plates 22, in fact they may be screws inserted through apertures formed in the plates and then run into the rear legs.

I desire that it be understood that various 75 changes may be made in the several details of construction shown without departing from the spirit of the invention and without sacrificing any of the advantages thereof which are new and useful.

Having now fully shown and described my invention, what I claim and desire to secure by Letters Patent of the United States, is—

1. A folding chair comprising front leg members, a back pivoted at its upper end to and between the upper end portions of the front leg members, rear legs pivoted at their upper ends to intermediate portions of the front leg members and being located at the inner sides of the same, a seat having its main body extending between and pivoted directly to the front leg members below the upper ends of the rear legs, the rear end of the main body of said seat being reduced in width and located between the upper ends of the rear legs, sliding connections between said reduced rear end of the main body of the seat and the rear legs, and sliding connections between the lower end of the back and the rear legs between the pivotal connections and the sliding connections of the seat therewith.

2. A folding chair comprising front leg members, a back pivoted at its upper end to and between the upper end portions of the front leg members, rear legs pivoted at their upper ends to intermediate portions of the front leg members and being located at the inner sides of the same, a seat having its main body extending between and pivoted directly to the front leg members below the upper ends of the rear legs, said rear legs having longitudinal slots and the rear end of the seat having lugs slidable in the slots, and sliding sleeve connections between the lower end of the back and the upper ends of the rear legs above the slots.

3. A folding chair, comprising front leg members, a back pivoted at its upper end to and between the upper end portions of the front leg members, rear legs pivoted at their upper ends to intermediate portions of the front leg members and being located at the inner sides of the same, a seat having its main body extending between and pivoted directly to the front leg members below the upper ends of the rear legs, said rear legs having longitudinal slots and the rear end of the main body of the seat being reduced in width and extending between the rear legs, said re-

duced portions having outstanding lugs slide-
able in the slots, the lower end of the back
being reduced in width and extending be-
tween the upper ends of the rear legs above
the seat, and sliding sleeve connections be-
tween the reduced lower end of the back and
the upper end of the rear legs above the slots
and the seat.

In testimony whereof I have hereunto sub-
scribed my name to this specification.

CLIFFORD J. MARSON.
